FOOT EXERCISER

Emil R. Mayland, Hutchinson, Kans.

Original application September 7, 1932, Serial No. 688,509, now Patent No. 1,972,308. Divided and this application May 17, 1934, Serial No. 726,147

1 Claim. (Cl. 272—57)

This invention relates to improvements in exercising devices and pertains particularly to devices designed for exercising the feet.

The primary object of the present invention is to provide a device whereby the metatarsal arch of the foot may be exercised for the purpose of re-adjusting the same and strengthening the muscles of the foot in this region when the same become weakened.

Another object of this invention is to provide a device for exercising the metatarsal arches in a regulated manner whereby the application of pressure to such arches for the purpose of restoring or replacing the same in their normal positions, may be gradually increased and regulated as required.

The present application constitutes a division of prior application, Serial No. 688,509, filed September 7, 1932, issued as Patent No. 1,972,308

September 4, 1934.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in elevation of my complete device showing the metatarsal arch exercisers in association with the exercising means for the longitudinal arches.

Figure 2 is a view in top plan of the complete exerciser.

Figure 3 is a sectional view taken on the line 3—3 of Figure 2.

Figure 4 is a sectional view taken on the line 4—4 of Figure 3.

Referring to the drawings wherein like numerals of reference designate corresponding parts throughout the several views, the device is illustrated as being of a portable character in that it is mounted upon a shiftable or movable base 1, although it is to be understood that the invention is not limited to this feature as it will be obvious that the elements making up the exerciser may be mounted directly upon the floor.

At the central portion of the device, upon the base 1, there is mounted the unit indicated as a whole by the numeral 2. This unit constitutes subject-matter for my prior application and will,

therefore, be referred to only in a general way to illustrate its use in association with the metatarsal arch exercisers which form the subject-matter of the present case.

The unit 2 is designed for exercising the longitudinal arches and broadly comprises a standard 3 having a head portion 4 across which an elastic band 5 extends. The ends of this band are secured at opposite sides of the standard 3 by the blocks 6, the band 5 being maintained in stretched condition across the standard, and the opposing faces of the blocks 6 which are shaped to receive the outer sides of the feet are shielded or covered by a cushion 7 preferably formed of sponge rubber. Upon either side of the central unit 2 are the units 8 which constitute the portions of the device devised for exercising the metatarsal arches of the feet. Each of these devices 8 comprises an arch band 9 having the downwardly and inwardly converging supporting legs 10 which are secured to the base 1 in the manner illustrated.

The inner face of each of the arches 9 and a portion of each of the supporting legs 10 therefore is covered with a cushion 11 of suitable character, preferably sponge rubber. One edge of the arch 9 has a portion turned upwardly or rounded, as indicated at 12, and the cushion 11 also extends over this portion of the arch.

Disposed forwardly of each of the arches 9 is a vertically arranged tubular standard 13. The lower end of the standard 13 is fixed in the base 1 and extending downwardly into the upper end of this standard adjacent each arch, is a stem 14 which carries upon its upper end a relatively large head 15 which has a rounded top surface as illustrated.

Beneath the head 15 is disposed a coil spring 16 which surrounds the stem and tubular standard and normally urges the head and stem upwardly. This spring 16 is relatively strong so that considerable pressure must be applied to force the head 15 down into contact with the upper end of the underlying stem 13.

In the use of the present exerciser, the foot is placed with the toes beneath one of the arches 9 so that the tops of the toes and the top of a portion of the foot will contact with the cushion 11. The spring supported head 15 adjacent the arch then contacts with the metatarsal area of the sole of the foot and the required upward pressure against this arch for the purpose of restoring it to normal condition is obtained by forcing the foot downwardly, using the point of contact of the toes with the arch cushion 11 as

a fulcrum. In this manner, it will be readily apparent that the metatarsal arch portion of the foot may be easily and thoroughly exercised and that the degree of exercise may be varied 5 by varying the amount of pressure with which the foot is forced against the spring supported head lying therebeneath.

What is claimed is:—

In a foot corrective device, a supporting base, 10 a rigid yoke member comprising an arcuate top portion and supporting side legs for the top, said legs being secured to the base and said yoke at one side having an upwardly curved edge portion, a padding disposed against the under

surface of said yoke and at the inner sides of said legs, said yoke being formed to fit the transverse top curvature of a foot, a tubular guide secured in said base at the side of the yoke having the upturned edge, a presser element having a rounded top surface and a supporting pin slidably disposed in said guide, the presser element being adapted to engage the under side of a foot having the toes engaged under said yoke, and a coil spring surrounding said pin and guide between the base and said head and normally urging the foot engaging head upwardly. 10

EMIL R. MAYLAND.
